PROPELLER FOR PROPELLING AND STEERING SHIPS

Albert Francis Anderson, San Francisco, Calif.

Application January 6, 1936, Serial No. 57,785

2 Claims. (Cl. 115—14)

My invention relates to improvements in ship propellers which operate submerged in water and in which thrust vanes are secured in positions about revolving centrifugal impellers in 5 such a manner as to cause thrusts produced by its action on the water to be exerted in directions that are parallel or approximately parallel to the planes in which the impellers are revolving, the planes being normal to the impeller 10 shafts.

The objects of this invention are as follows:

First: To provide impellers secured to shafts by which they may be revolved by means of 15 motors or engines;

Second: To provide castings which position thrust vanes about said impellers and which also form conduits for conveying water in and out of said impellers;

Third: To provide journals for positioning said 20 impellers and impeller shafts;

Fourth: To combine all parts of such propellers into units that can be attached to ships and 25 propel them; and

Fifth: To produce propellers in which none 30 of the propulsive thrust need be imposed on the propeller shaft or the revolving impellers, but in which all of the propulsive thrust may be transferred directly to the ship through vanes attached to its hull.

Other objects and advantages of this invention 35 are as follows:

One: To produce propellers which may be mounted, in a practical manner, anywhere on ships' hulls, such as on the sides, bottoms, and 40 ends of the same, and which can be employed on ships having the usual forms of ships' propellers as well as those without the same.

Two: To provide a means for propelling ships 45 which operate as hydroplanes by producing propellers which may be attached to their bottoms where they have access to water.

Three: To provide a means for expending more 50 energy for propulsion purposes without straining the hulls of ships by employing a number of propellers of my invention of the character described which will distribute the thrust strains thereon.

Four: To produce propellers which may operate 55 at high rotative speeds without causing severe vibrations in ships' hulls or cause water to pound unduly against the same.

Five: To produce propellers of the character 60 described which may be attached to ships without altering the construction thereof.

Six: To produce such propellers which may

be attached to ships in conjunction with outboard propelling motors.

Seven: To produce propellers which are removable and replaceable by employing air-chambers in ships' hulls into which they may be 5 withdrawn and replaced while the ships remain afloat.

Eight: To produce propellers which may steer ships so that a ship need not carry a rudder and the weight of the supports and mechanism 10 thereof.

Nine: To construct propellers which may be operated by high speed propelling motors without resorting to the use of reduction gears.

Ten: To construct propellers which do not 15 need thrust bearings and their shafts for transmitting the propulsive thrust to ships.

Eleven: To produce propellers whose impellers and their driving motors are capable of being revolved at speeds sufficiently great as to cause 20 gyroscopic forces to be generated which may add to the stability of ships.

Twelve: To produce propellers which do not necessitate the burdening of ships with long and heavy propeller shafts together with their 25 bearings and supporting frames.

Thirteen: To combine the various parts of my propellers and their driving motors into compact propelling units and to provide for the lubrication of their shafts and bearings as well 30 as to seal the same against leakage of water from outside the ships on which they may be mounted.

Fourteen: To combine the thrust vanes of my propellers and form casings which surround their 35 impellers and which may be secured to the outside surface of ships' hulls, either immovably or movably by means of trunnions upon which said casings may be turned when acted upon by turning gears situated inside the hulls of ships. 40

Fifteen: To construct propellers for high speed ships which do not jeopardize the safety of ships by over-stressing the materials of which their 45 revolving parts are made.

Sixteen: To produce propellers which can operate at extremely high speeds with unimpaired efficiency.

Seventeen: To construct propellers which may be suitable for life-boats, divers'-boats, work-boats, and fishing-boats, and whose revolving 50 parts may be shielded from injury by thrust vanes which form casings around said parts and which also serve to prevent lines and fishing nets from being injured by the same.

Eighteen: To form propellers which are adapt- 55

able to all parts of ships' hulls thereby enabling them to be located strategically thereon for the purpose of reducing the resistance and wave-making proclivity of ships.

5 I attain these objects and advantages by means of the propellers illustrated in the accompanying drawings in which Figure I is a cross-section of my propeller and of the fragmentary portion of a steel ship to which it is attached and Figure II is a similar view of my propeller having its thrust-casing trunnioned so as to enable it to be turned with respect to the ship.

In both figures similar numerals refer to similar parts.

10 15 It may be assumed that my propeller is shown mounted on the bottom of a ship, numeral "1" indicating the steel hull plating of the same, in both figures.

10 Referring to Figure I; impeller 2, positioned outside the ship, is keyed to shaft 3 by which it may be revolved when driven by motor 4 which is situated inside the hull of the ship.

20 25 The bearings of motor 4 restrict the end-play of shaft 3 which is further positioned by bearing 5 which is fitted with a stuffing-box 6 at its upper end and a seal 7 at its lower end for the double purpose of excluding water and retaining a lubricant which also protects the shaft from corrosion.

30 35 Air under pressure may be maintained in a chamber formed by walls 8 enclosing the propeller or the entire propelling unit. Said chambers may serve to restrict leakage of water into the ship as well as to facilitate the removal and the replacement of the propeller or propeller parts while the ship is afloat in water.

Thrust-casing 9 with its diaphragm 10 is secured to the ship through frame 11 which is the common support for the entire propelling unit.

40 45 Thrust-casing 9 comprises the following parts, a double inlet 12-12 fitted with vanes 13, a compartment enclosing impeller 2 which is partially surrounded by a volute conduit 14 having its outlet 15 divided by thrust vanes 16-16 and 17 and also by partitions 18-18.

Thrust vanes 19-19 are not incorporated in the thrust casing 9 but are attached to the ship independently.

50 Referring to the same figure and assuming that the propeller there shown is in operation and is propelling the ship to which it is attached in a direction corresponding to a movement from right to left with respect to the figure; the functioning is as follows:

55 60 65 Through inlet 12-12 water enters impeller 2 and is discharged by its motion through outlet 15, most of it leaving by way of the circular conduit 14. The reactionary forces thereby produced are combined into a unified thrust with the aid of vanes 13, 16-16, 17 and 19, through which vanes together with conduit 14 and the thrust-casing 9 as a whole the thrust is imparted to the ship as its propulsive thrust.

65 70 75 Referring to Figure II which shows my propeller having its thrust-casing 20 secured to the supporting frame and thence to the ship by means of a trunnion 21 about which said thrust casing may be turned while the propeller is in operation and thereby alter the direction of the resulting thrust with respect to the ship on which it is mounted and propel it in various directions, ahead, astern, or sideways; said propeller also having the essential features of the one just described and functioning in the same manner.

I prefer to form the apparatus for turning the above mentioned thrust-casing of a worm-wheel 22 which is keyed to trunnion 21 and its worm 23 which may be operated by a handwheel or other means.

5 Trunnion-bearing 24 is provided with packing 25 and a water-seal 26 for the purposes of retaining a lubricant under pressure and excluding water from contacting the surfaces of the trunnion and bearing.

10 Thrust-casing 20 is secured in position by nut 29 fitted on the upper end of trunnion 21.

15 Diaphragm 27 together with frame 28 supports the entire propelling unit and transmits its thrust to the ship.

15 The several views of another form of my propeller are shown in Figures III, IV, V, and VI; of which Figure III is a sectional elevation, (a view similar to Figures I and II), of my propeller having but one inlet to its impeller, and Figure 20 IV is a sectional plan view (or horizontal section) of the same propeller in which the thrust vanes are shown in cross-section. Figures V and VI are exterior views. Figure V, a rear elevation and Figure VI, a side elevation.

25 In these figures, like numerals are employed to designate like parts and the parts in these figures that correspond to those shown in Figures I and II are indicated by the same numerals; thus, 1 indicates the hull plating of a ship, 30 2 the centrifugal impeller, 3 the propeller shaft, 9 the thrust casing, 12 the inlet, 14 the semi-circular conduit, 15 the outlet aperture, and 17 the thrust vanes.

35 In the several views a fairwater 30 is shown extending from thrust casing 9, as a continuation of the streamlining of the same.

In Figure IV, the adaptation of the thrust-vanes 17, to the purpose of deflecting the fluid from the impeller 2, into a rearward direction 40 is apparent. The propulsive thrust imposed on the vanes while deflecting this fluid is communicated to the ship thru thrust-casing 9, which forms a body for holding the various parts of the propeller together.

45 Thrust vanes 17 are not designed to act as diffusing vanes which are commonly employed on centrifugal pumps for converting the velocity head of the fluid as it leaves the impeller, into pressure head in the pump case; but are formed 50 to serve their purpose as mentioned above without materially decreasing the velocity of the fluid after it leaves the impeller 2; and it may serve to increase the velocity instead.

55 However, it is to be understood that if, and when, the velocity of the fluid leaving the impeller is increased, it must be increased immediately after leaving said impeller while being deflected by the thrust vanes 17 and not as in jet propellers where the velocity of the fluid leaving the impeller is first reduced and the energy thereof is converted into potential energy, then afterwards the energy is again converted into kinetic energy as the fluid is ejected thru nozzles.

65 In my propeller these changes in the velocity of the fluid and the alternations or reversals of the accelerations of the same are reduced to a minimum or are practically eliminated as are also the losses in efficiency incurred thereby. The 70 fluid in my propeller has its velocity steadily increased beginning at the instant the fluid enters the propeller until it is discharged past the thrust vanes 17; and because of the embodiment of this principle, the size of the apparatus 75

becomes greatly reduced which is attended with many advantages such as reduced weight, cost and bulk and reduced resistance to motion thru the fluid in which it operates, while the propulsive efficiency is increased.

5 The semicircular conduit 14, is also designed so as to embody the above mentioned principle and may be regarded as a modified thrust vane. It does not serve as a scroll case of a centrifugal 10 pump as its appearance may suggest; inasmuch as it does not serve to convert the velocity head of the fluid leaving impeller 2 into pressure head; but contrawise; it may serve to increase the velocity of said fluid still further; or it may 15 serve simply to deflect the flow of the fluid without altering its velocity and in either case, the desired thrust is realized.

Variations in the width of the opening or outlet 15 where the thrust vanes are situated can be made by inserting filler pieces 31 indicated by dotted lines, thereby causing in effect, what corresponds to an increase in pitch, in the case 20 of a screw propeller.

One characteristic of my propeller is that all 25 the propulsive thrust generated by the same may be delivered to the ship thru immovable vanes, which I have termed "thrust vanes", and consequently none of the propulsive thrust need be imposed on the revolving blades of the impel-

ler; thereby allowing the pressures on said blades to remain uniform or balanced thruout each revolution of the impeller.

It is intended that the forms of my invention shown and described herein are to be taken as preferred examples of the same and that various changes in the shape, size, design and arrangement of the device and its parts may be resorted to without destroying the invention, without departing from the spirit of the invention or from 10 the scope of the subjoined claims.

Having thus described my invention, I claim:

1. A ship propulsion mechanism comprising a power shaft, a fluid impeller fixed on said shaft, a casing having inlet and outlet openings surrounding said impeller and adapted to be secured to a ship and vanes fixed to said casing at the outlet opening, the thrust resulting from the operation of said mechanism being normal to the axis of rotation of said power shaft for the propulsion of the ship.

2. A ship propulsion mechanism as defined in claim 1 including means for securing said casing to said ship comprising a trunnion attached to said casing and a trunnion bearing concentric 25 to said shaft and means for turning said trunnion whereby said casing and vanes will be turned relative to the ship.

ALBERT FRANCIS ANDERSON.
